UNITED STATES PATENT OFFICE.

CARL ROBERT VIEHOFER, OF INSTERBURG, PRUSSIA, GERMANY.

LESSON-DISPLAYING DEVICE.

SPECIFICATION forming part of Letters Patent No. 358,761, dated March 1, 1887.

Application filed May 6, 1886. Serial No. 201,302. (No model.)

To all whom it may concern:

Be it known that I, CARL ROBERT VIEHOFER, of the city of Insterburg, Kingdom of Prussia, German Empire, have invented certain new and useful Improvements in Object-Teaching Apparatus, of which the following is a specification.

This invention relates to certain new and useful improvements in apparatus to be used in object-teaching; and the object of my invention is to provide an apparatus of this kind which facilitates instructing scholars in writing, reading, &c., and improves and trains their memory.

15 The invention consists in the combination, with a screen having an opening which can be closed by a shutter, of a drum on which removable strips are held bearing the different names, inscriptions, pictures, &c., which drum 20 revolves behind the screen, and is operated by the same mechanism which operates the shutter for closing the opening in the screen, all as will be fully described hereinafter, and pointed out in the claims.

25 In the accompanying drawings, Figure 1 is a side view of an improved apparatus for object-teaching. Fig. 1^a is a front view of the same. Fig. 1^b is a rear view of the screen. Fig. 2 is a cross-sectional elevation of the same, 30 parts being broken out. Fig. 2^a is a cross-sectional view of one of the plates fastened on the drum for the purpose of receiving the slides. Fig. 2^b is a front view of the frame and the drum. Fig. 3 is an enlarged view of 35 the end of the drum and a cross-sectional view of the screen. Fig. 3^a is a sectional plan view of the parts shown in Fig. 3. Fig. 4 is an enlarged detail sectional view of the mechanism for shifting the drum and operating the shutter. Fig. 4^a is a sectional plan view of the parts shown in Fig. 4. Fig. 5 is a side view of the lever for operating the drum and shutter, parts being broken out and others in section. Fig. 5^a is a plan view of the same.

45 Similar letters of reference indicate corresponding parts.

The frame B is fastened on an extensible standard, E, having a suitable base or leg, and in the frame B the shaft C is journaled, on 50 which is mounted the polygonal drum A. The frame B is provided with arms C', adjacent to the ends of the drum, on which arms a verti-

cal screen, S, is provided, which is preferably colored green. The screen-frame is formed of a series of rods hinged together by means of 55 hinges t and braced by means of rods L. Said screen is provided with an opening or slot, D, which can be closed by means of a shutter, K, hinged on the outside of the screen, above the top edge of the slot D, in such a manner that 60 it can swing up and down, the opening D being closed when the shutter is lowered. On each side of the polygonal drum A a metal or other strip, a, is held, which is provided at one end with a slot for receiving a button, a', 65 at one end of the side of the drum, the opposite end of the strip a being held by means of a latch, a². Said strips a may have grooved flanges along the longitudinal edges and outer surface, so as to adapt them to hold the cards 70 or letter-plates a³, forming the words.

If desired, the words, pictures, &c., may be painted, printed, or otherwise produced on the strips a themselves, in which case the strips need not be flanged. The strips can be easily 75 removed from the sides of the polygonal drum and replaced by others. On one end of the hinged shaft of the shutter k a grooved pulley, s, is mounted, to which one end of a chain, m, is fastened, which is also passed through an 80 opening in the screen S, passed over a pulley, r, journaled at the back of the screen, and is then secured to a lever, i, pivoted at i' to one of the arms C' projecting from the frame B. The lever i is provided, at that end opposite 85 the one at which the chain m is fastened with an eye, i², for receiving a pin, p², projecting from the inner end of a lever, p, pivoted at p' to an arm, F, projecting laterally from the arm C'. A forked lever, q, is pivoted at q' to 90 the arm F, and through the ends of the prongs of the fork and through the lever p, which passes between said prongs, a pin, p², is passed, as shown in Fig. 5^a. A spring, w, is fastened to the bottom edge of the lever p and rests 95 against a screw, q², screwed on the outer end of the lever q, and provided at its upper end with a button, q², by means of which screw the tension of the spring can be adjusted. The lever p is also provided at its inner end with a pin, p⁴, which projects into a slot, g, on one end of a lever, f, pivoted at f' to the inner side of the arm C', to which lever a dog or pawl, e, is pivoted at that end opposite the one 100

provided with the slot *g*, which dog or pawl is provided in its swinging end with a notch for receiving pins *d*, arranged in a circle on the end of the drum and around the shaft *C*. A 5 spring, *v*, is fastened to the edge of the lever *f* and acts on the pawl or dog *e*, and a stoppin, *u*, projects from the side of the arm *C'*. A sliding bolt, *R*, is mounted to slide between suitable guides on the inner side of the end 10 piece of the frame *B*, and is provided with a downwardly-projecting lug, *n*, against which one end of a spring, *v'*, acts, fastened to the inner side of the frame *B*. On its upper surface the sliding bolt is provided with an upwardly-projecting lug, *n*, having a rounded end, so as to adapt it to fit against the pins *d* of the drum. The lever *p* projects through an 15 aperture, *o*, in the arm *C'*.

The operation is as follows: When the shutter *k* is closed—that is, lowered—one of the pins *d* rests in the notch in the upper end of the pawl *e*, and the notched end of the arm *e'* of the lever *f* rests against one of the pins *d*, as shown in Fig. 4. The lug *n* on the top of 20 the sliding bolt *R* also rests against one of the pins *d*. To open the shutter the knob or button *q*² is raised, whereby the pin *p*³ on the end of the lever *p* is also raised, whereby the inner end of the lever *i* is moved upward and the outer 25 end, or end adjacent to the screen, is moved downward. The chain *m* is pulled down, and thereby the roller *s* is turned in the direction of the arrow, Fig. 3, whereby the shutter is 30 swung up, the levers *f* and *i* being in the position shown in Fig. 3 and in dotted lines in Fig. 4. The letters, pictures, &c., on one of the sides of the polygonal frame can now be 35 seen through the slot *D* of the screen *S*. To swing the shutter down for the purpose of 40 closing the slot *D*, the knob *q*² is pressed downward, whereby the pin *p*³ on the end of the lever *p* is moved down, as is also the inner end of the lever *i*, whereby the chain *m* is 45 slackened, permitting the shutter to swing down under the action of its own weight and to close the slot *D*. The pawl *e* is moved upward, and as its end is engaged by one of the pins *d* the drum is revolved the distance of one pin *d*. The pawl *e*, acting on the bevelled end of the slide-bolt *R*, pushes the same 50 back so as to disengage the pin *d* from the lug *n*. The next lower pin, *d*, in turning strikes against the bevelled end of the bolt *R* and pushes the same back slightly, and then the 55 spring *v'* acts on the bolt and presses the lug *n* against a pin, *d*, thus locking the drum in place. The spring *v* serves to hold the levers *p* *q* in line. Thus by a single operation

the shutter *k* can be raised so as to expose the name, picture, &c., on one of the sides of the 60 drum and at the same time the pawl for revolving the drum is lowered, and by another operation the shutter is released to swing down and the pawl is moved upward for the purpose of rotating the drum. The shutter 65 in swinging up and down strikes the screen and produces a sound which calls the attention of the scholars to the screen.

Having thus described my invention, I claim as new and desire to secure by Letters Patent— 70

1. In an apparatus for object-teaching, the combination, with a slotted screen, of a shutter for closing the slot in the screen, a drum mounted to revolve behind the screen, and mechanism for revolving the drum and operating the shutter on the screen, substantially 75 as shown and described.

2. In an apparatus for object-teaching, the combination, with a slotted screen, of a shutter for closing the slot in the screen, a drum 80 mounted to revolve behind the screen, pins projecting from one end of the drum, a pawl device for revolving the drum, a lever for operating the shutter, and a lever for operating the pawl device and the shutter-operating 85 lever, substantially as shown and described.

3. In an apparatus for object-teaching, the combination, with a slotted screen, of a shutter for closing the slot in the screen, a drum 90 mounted to revolve behind the screen, pins projecting from the end of the drum, a pivoted lever carrying a pawl for engagement with the pins of the drum, a pivoted lever connected with a chain secured to a pulley on the shaft of the shutter, and a compound lever 95 for operating the two above-named levers, substantially as shown and described.

4. In an apparatus for object-teaching, the combination, with a slotted screen, of a shutter for closing the slot in the screen, a drum 100 mounted to revolve back of the screen, pins projecting from one end of the drum, a sliding bolt for engagement with the pins, a pivot-lever having a pawl which can act on the pins for the purpose of revolving the drum, and 105 mechanism for operating the shutter with the same devices that revolve the drum, substantially as shown and described.

In testimony that I claim the foregoing as my invention I have signed my name in presence of two subscribing witnesses. 110
